UNITED STATES PATENT OFFICE.

HARRY N. FOWLER, OF CHICAGO, ILLINOIS, ASSIGNOR TO MABEL C. FOWLER, OF CHICAGO, ILLINOIS.

SEARCH-LIGHT LAMP.

1,257,837.

Specification of Letters Patent.

Patented Feb. 26, 1918.

Application filed March 2, 1916. Serial No. 61,596.

To all whom it may concern:

Be it known that I, HARRY N. FOWLER, a citizen of the United States, residing at Chicago, in the county of Cook and State of Illinois, have invented certain new and useful Improvements in Search-Light Lamps, of which the following is a specification.

My invention relates to dirigible lamps of the type usually equipped with a reflector and known as searchlights, and is particularly well adapted for use upon the wind shields of automobiles, although it is equally suited for use upon vehicles of any other kind, or on motor boats, and for use in any situation where it is desirable to readily manipulate and adjust the lamp structure to throw the rays of light in any desired direction. The object of my invention is generally to produce an easily manipulated, well-balanced, efficient and sightly lamp of this type, to which end I have devised a novel arrangement of hollow jointed tubing members forming a universally adjustable supporting bracket, the joints of which are frictionally held under yielding but firm spring pressure, whereby the lamp may be swung to any desired position and will be retained in adjusted position. Within this hollow adjustable bracket or lamp mounting, I arrange the electric conductor for the light,—or gas tubing, if the lamp be a gas lamp,—the wire, or tubing, as the case may be, in this manner being concealed and out of the way, and being protected from the elements and chafing, thus preventing short-circuiting or breakage.

A further feature of my invention consists in the provision of a mirror mounted upon the back of the lamp structure and which may of course be swung with the lamp upon the adjustable mounting to give a view of objects in a rearward direction from the observer at any desired angle.

With the foregoing object and advantages in view my invention consists in the novel combination, construction and arrangement of parts recited in the appended claims, in which different features of my invention are defined.

Of the drawings, Figure 1 shows a top view of a preferred form of my improved lamp and the adjustable mounting by which it is attached to the side member of a wind-

shield such as is commonly used on automobiles; Fig. 2 is a horizontal view of the same from the point of view of the driver of the machine; Fig. 3 is a section on the line 3—3 of Fig. 1, showing the construction of the bracket joints; Fig. 4 is a central section through the operating knob at the rear of the lamp showing the arrangement and construction of the switch for the electric lamp; Fig. 5 shows my invention applied to a gas lamp; Fig. 6 is a rear view of a simplified form of lamp and mounting, partly in section; Figs. 7 and 8 are detail views showing the construction of the electric switch housed in the operating knob; Fig. 9 a top view of the clamp shown in Fig. 6; and Fig. 10, a fragmentary view showing a different manner of assembling certain parts illustrated in Fig. 3.

Similar reference characters indicate similar parts on all the figures of the drawing.

In the particular and preferred embodiment of my invention which will first be described and which is illustrated in Figs. 1, 2, 3 and 4, the lamp is an electric lamp adapted to be secured to one of the side members 1 of the windshield of an automobile, to which end it is provided with clamp members 2 and 3, clamped together by a pair of bolts 4—4. Rigidly clamped to a rearwardly projecting lug 3^a of the clamp member 3 by means of a bolt 5 is an L-shaped bracket piece 6, the horizontal portion of which is bored to form a box for the reception of a vertical rotatable tube 7, which tube and box members together constitute a pivot bearing forming part of the adjustable lamp support and electric wire conduit. A nut 8, forming a lower abutment, is screwed firmly on the lower end of this tube, and the upper end is screwed or otherwise firmly secured to the quarter-turn coupling 9, the base of which forms an upper abutment. Between such upper abutment and the top of the bracket piece 6 is interposed a strong helical compression spring 10 coiled around the tube 7 and enclosed within telescoping casing shells 11 and 12, washers 13 being provided on the opposite sides of the bracket piece and between the base of the coupling and the upper shell 11 to receive and distribute the thrust of the spring. If desired, however, the

spring may be arranged below the bracket piece and between it and the nut 8, as shown in Fig. 10. It is manifest that in either case the tension of the spring will react 5 against the bracket piece 6 at one end of the spring and the abutment on the tube (whether the upper abutment or lower) at the other end of the tube to draw the other abutment against the other side of the 10 bracket piece, and thus yieldingly and frictionally restrain movement of the tube within the box member of the bearing.

To one side of the casing 14 of the lamp, near its front edge, is riveted or otherwise 15 secured a casting 15 which is formed with a hub 16 revolvably mounted upon a horizontally disposed short tube 17 constituting one member of a horizontal pivot bearing. One end of this tube is screwed into 20 the upper end of the quarter-turn coupling 9, the other end having firmly screwed upon it a nut 18. Interposed between the outer end of the hub 16 and the end of the coupling are a spring 19, telescoping casing 25 shells 20 and 21, and washers 22 22 at opposite sides of the shells, and between the inner end of the hub 16 and the nut 18 is placed a washer 23; the whole forming a spring-tensioned friction joint similar to 30 that already described.

The lamp casing may be of the usual form illustrated, or any other suitable design having a reflector arranged within the casing, and in the present instance such 35 casing is closed at the front with a glazed door and provided with a reflector 24 serving to concentrate the rays of light into a beam. The insulated conductors 25 carrying current for the electric light 26 are led 40 in through the conduit formed by the tubes 7 and 17 and coupling 9 into the space between the casing 14 and reflector 24, where they are secured to the terminals of an electric switch whereby the current may be 45 directed through the light 25, or cut off. The switch, in the present instance, and preferably, is located in a manipulating knob or handle 27, projecting from the rear end of the lamp casing, and is of the push-button type. The details of the switch form 50 no part of the present invention, but may suitably be of the construction illustrated, in which the push-button 28 is held in its opposite positions by the spring 29, the current being "off" in the outer position, and in which, when the push-button is in inner position, the spring contacts 30 connected with the conductors 25 will make contact with the terminals of the lamp.

60 The conductors 25, for a purpose which will hereinafter be explained, are equipped at a convenient distance below the clamp mounting with the plug member 43 of a plug and socket connection, the socket member, which is in connection with the source

of electric current, being secured to the dash board of the automobile,—assuming that the lamp is to be used upon such a vehicle.

Upon the top of the casing 14 is fixed, by means of the bracket 31 or other suitable 70 means, an upright mirror 32, facing rearwardly. By means of the knob 27 the driver of the car can swing the lamp structure upon the tube 7 as an axis, and also tilt it upon the tube 17, thus turning the 75 mirror into position to reflect any object to the rear or in a rearward direction, or can direct a beam of light in any desired direction, turning the light on or off with the greatest facility while doing so.

It is obvious that my improved lamp fixture may be as readily applied to the left hand frame member of a windshield as the right, since if the bracket piece 6 be clamped tight half around from the position shown, 85 and the lamp casing and parts carried by it be also swung half around, the lamp may be mounted at the left hand side of the windshield with the same relative position of the parts as on the right hand side.

90 While I have illustrated and described as the preferred form of my invention an electric searchlight in which the electric lamp is supplied with current through an insulated conductor, it is obvious that it may readily be applied to gas or petrol lamps in which the illuminant is conducted to the burner through a flexible tube, as illustrated in Fig. 5. In this modified form of my invention the flexible tube 33 is a conduit 100 through which the gaseous illuminant is conducted to the burner 34, the tube being arranged within the hollow universal bracket in the same manner as that heretofore described.

105 While the tubular construction of the lamp bracket finds its highest utility in connection with a searchlight having an outer casing and a reflector arranged within such casing, and in which the conductors for the 110 lamp are led through the bracket members and the space between the lamp casing and the reflector, it is obvious that this form of universal mounting may be usefully employed with a single-piece searchlight in 115 which the interior of the casing is formed and finished to constitute a reflector. In Figs. 6 and 7 I have illustrated such a form of searchlight mounted upon a somewhat simplified form of mounting including a 120 pair of clamping members 35 and 35^a adapted to be clamped upon one of the vertical members of the windshield of an automobile. A bracket piece 36 is detachably secured by a horizontal cap screw or bolt 36^a 125 to the clamp member 35^a, said bracket piece being formed with a vertical bore or socket to receive the depending portion of an L-shaped tubular structure comprising the vertical tube section 37, the L-coupling 38 and 130

the horizontal tube section 39. A strong helical spring 40 confined between the lug 36^a and coupling 38 by a nut on the lower end of the tube section 37 provides a yielding frictional pivot bearing of said section in the lug, and a similar spring 41 between the other end of the coupling and a hub or socket 42 secured to the casing of the lamp affords a similar horizontal pivot bearing 10 for the lamp. The last mentioned spring is confined by a nut on the tube section 39 inside the socket 42, which nut bears against an internal annular shoulder within said socket.

15 The electric cable for supplying current to the lamp is in this form of lamp led into the casing by a rotatable member 44 which is at once a switch and a connecting plug. A similar or suitable plug 44^a at the other 20 end of the cable is provided to form a separable connection with a convenient fixed socket and connect the cable with the source of electric current. The plug 44 is equipped with a pair of radial pins 45, adapted, when 25 the plug is inserted axially into a tubular bushing member 46 secured centrally within the knob 47 and forming the socket member of the connection, to pass through longitudinal slots 48, or openings into connecting 30 transverse slots 49. Spring pressed plungers 50 in connection with the lamp terminals bear against the inner end of the plug and in one of the two opposite positions at the ends of the slot 49 bear against 35 the plug contacts and complete the circuit through the lamp, and in the other extreme position are insulated and break the connection. The ends of the slot 49 are formed with slight outward notches so that the pressure of the plungers 50 will yieldingly maintain the plug in either one of the "off" or "on" positions to which it may be turned. The lamp and mounting, as before explained, are made so as to be readily detached 40 from the supporting bracket, so that by the use of an extension cord equipped at its ends with plug and socket connecting members adapted to cooperate with the plug 44^a and the fixed supply socket, the detached 45 lamp may be carried to any point permitted by the length of the cord to give light in places otherwise inaccessible.

The plug and socket connections afforded by the plug member 43, before mentioned in 50 describing the preferred form of lamp, illustrated in Figs. 1, 2, 3, and 4, and the readily detachable connection formed by the bolt or set screw 5, are likewise provided for the purpose of enabling an extension cord 55 equipped with corresponding plug and socket members to be used in the manner just above described. The portability thus afforded enables the lamp to be used any place around or near the machine, to discover 60 the cause of troubles which may occur,

or for any other purpose, thus considerably increasing the usefulness of the device.

I claim:

1. In a device of the character described including a pivot bearing comprising a pivot member and a box member arranged to support a lamp casing, means for yieldingly and frictionally restraining relative rotation of the bearing members comprising abutments fixed to the pivot member of the bearing on opposite sides of the box member, a spiral compression spring surrounding the pivot member and interposed between the box member and one abutment, and a telescoping shell member inclosing said spring and forming a casing therefor.

2. In a device of the character described including a pivot bearing comprising a tubular pivot member and a box member arranged to support a lamp casing and an electric light arranged therein, means for yieldingly and frictionally restraining relative rotation of the bearing members comprising abutments fixed to the tubular pivot member of the bearing on opposite sides of the box member, a spiral compression spring surrounding said pivot member and interposed between the box member and one abutment, and conductors for said light disposed within said tubular pivot member.

3. A device of the character described comprising a vertical tubular bearing member rotatable in a fixed support and equipped with an abutment at its bottom, a quarter-turn coupling secured to the top of said vertical tubular member, a horizontal tubular bearing member secured at one end to said coupling and at its other end equipped with an abutment, a lamp casing pivotally mounted on said horizontal member, spring-tension means co-operating with the base of the vertical portion of the coupling and the abutment at the bottom of the vertical tubular member for frictionally restraining rotation of such member in its support, and spring-tension means co-operating with the base of the horizontal portion of the coupling and the abutment at said other end of the horizontal tubular member for frictionally restraining rotation of the lamp casing mounted thereon.

4. A device of the character described comprising a laterally extending supporting bracket, a vertical cylindrical pivot member rotatably mounted in said bracket, a relatively long spiral compression spring of a plurality of turns surrounding said pivot member and arranged to yieldingly restrain movement of the pivot member in its bearing, a horizontal cylindrical pivot member secured to and forming a continuation of said first mentioned pivot member, a lamp casing equipped with means whereby it may be manually directed and with a light and mounted to rotate on said horizontal pivot

member, and a relatively long spiral compression spring of a plurality of turns surrounding said pivot member and arranged to yieldingly restrain movement of the lamp casing on said horizontal pivot member.

5. A device of the character described comprising a laterally extending supporting bracket; a vertical cylindrical pivot member rotatably mounted in said bracket, 13 and having abutments at its top and bottom, a relatively long spiral compression spring of a plurality of turns surrounding said pivot member and compressed between said supporting bracket and one abutment, a 15 horizontal cylindrical pivot member secured

to and forming a continuation of said first mentioned pivot member, said horizontal member having abutments near its opposite ends, a lamp casing equipped with means whereby it may be manually directed and with a light and mounted to rotate on said horizontal pivot member, and a relatively long spiral compression spring of a plurality of turns surrounding said pivot member and compressed between the outer abutment and said lamp. 20 25
